UNITED STATES PATENT OFFICE

104,020

DESIGN FOR A SHOE

Hyman M. Edelstein, Brooklyn, N. Y.

Application August 1, 1936, Serial No. 64,190

Term of patent 3½ years

To all whom it may concern:

Be it known that I, Hyman M. Edelstein, a citizen of the United States, and residing at Brooklyn, county of Kings, State of New York, have invented a new, original, and ornamental Design for Shoes, of which the following is a specification, reference being had to the accompanying drawing, forming part thereof.

Fig. 1 is a plan view of a shoe, showing my new design.

Fig. 2 is a side elevational view of the same shoe.

The shoe embodies a rope-like element extending through the roll ornamentation, which in turn terminates in tubular elements at each side of the shoe.

I claim:

The ornamental design for a shoe as shown and described.

HYMAN M. EDELSTEIN.
